CHEMICAL APPARATUS

Walter O. Luertzing, Vineland, N. J., assignor to,
Lurex Manufacturing Company, Vineland, N. J.,
a corporation of New Jersey

Application March 24, 1948, Serial No. 16,711

3 Claims. (Cl. 285—161)

1

This invention relates to glass articles adapted to be assembled with others with air-tight connections of the ground tapered plug and socket type, examples of such articles being lengths of tubing employed in chemical apparatus, adapters, stoppers, and the like. More particularly, the invention is concerned with a novel glass article having a frusto-conical ground surface, the article being so formed that it is not liable to be damaged by chipping at the small end of the ground surface during handling and use. The invention also includes a method, by which such articles may be made easily and at no more cost than prior similar articles. The new articles may be of various kinds, depending upon the use to which they are to be put, and, since a length of tubing with a ground tapered portion of plug shape is typical, that form of the article of the invention will be illustrated and described in detail.

At the present time, it is the practice, in making lengths of glass tubing to be used in chemical apparatus and provided with ground frusto-conical surfaces, to heat the end portion of a straight length of tubing and work the softened glass by a suitable tool to form a blank having a portion of increased wall thickness, which terminates at the end of the blank and has an outer diameter tapering toward that end. The end surface of the blank is smooth and, in finishing the article, the outer surface of the thickened portion is ground to frusto-conical form with the ground surface meeting the end surface. The end of the blank is so formed that the angle between the ground and smooth end surfaces on the article is ordinarily a right angle or less and this makes the outer end edge of the article so sharp that it is delicate and easily damaged by chipping.

The present invention is directed to the provision of a glass article with a ground surface of frusto-conical form, which is not liable to be damaged along the edge of the surface at the small end of the ground surface. The desired result is achieved by giving the blank, of which the article is to be made, a novel shape at the end of the portion to be ground and then grinding the blank in such a manner that the surface of the article beyond the end of the ground surface is smooth, extends outwardly beyond the ground surface, and, with the latter, defines an angle greater than a right angle.

For a better understanding of the invention, reference may be made to the accompanying drawing, in which

Fig. 1 is a view in longitudinal section through

the end portion of a tubular blank used in the production of an article of the invention;

Fig. 2 is a longitudinal sectional view through the finished article made from the blank of Fig. 1; and

Fig. 3 is a side elevation, on a reduced scale, of the end portion of the finished article shown in Fig. 2.

The article shown in the drawing is a length 10 of glass tubing, which is provided at one end with a portion of plug form having a frusto-conical ground surface, so that the end of the tubing may be inserted in a ground tapered socket, for example, in the neck of a vessel, to make an air-tight connection. In the production of such an article, a length of straight tubing 10 is used and the end portion of the tubing is heated and worked with a tool to form an enlargement 11 of increased wall thickness and having an outer circumferential surface 12 of frusto-conical form. At its end, the surface of the blank is formed with a circumferential zone 13, which extends backwardly from the end and outwardly at an acute angle to the axis of the tubing. From the inner edge of the zone extends a curved surface 14 which connects the surface of the zone with the inner surface 15 through the blank.

To convert the blank to the finished article, the outer surface of the portion of increased thickness is ground to frusto-conical form, the taper of the ground surface corresponding to that of the socket in which the article is to be mounted. In the grinding operation, a quantity of glass is removed circumferentially from the blank and the operation is restricted, so that the extension of the ground surface will intersect the zone 13. As a result, the article has a smooth end surface 16, which projects outwardly beyond the small end of the ground surface and inhibits chipping of the adjacent end of the article. The taper of the ground surface is such that a generatrix of the surface makes a small acute angle with the longitudinal axis of the article, and the angle α between the ground surface and the surface of the zone 13 at the end of the article or a plane tangent to the smooth end surface of the blank at its intersection with the ground surface, is greater than a right angle. As a result, the outer end edge 17 of the article is comparatively blunt and not liable to be damaged during shipment or use of the article.

It will be apparent that the zone 13 need not be of frusto-conical form and ordinarily it is not precisely so but of somewhat spherical curvature on a large radius. The shape of the article be-

yond the small end of the ground surface is not critical so long as the angle α is obtuse, and the edge 17 correspondingly blunt.

In the drawing, the article has been illustrated as of tubular form with the ground surface close to one end. In the case of a stopper made in accordance with the invention, the body of the stopper will, of course, be solid. The shape of the central portion of the end of the stopper is unimportant, so long as the end surface includes 10 the circumferential zone, which, with the frusto-conical ground surface, defines an obtuse angle.

I claim:

1. A glass article which comprises a tubular body having a smooth unground circumferential surface at one end, said surface including a zone having an outer surface portion extending backwardly from said end and outwardly at an acute angle to the axis of the blank and an inner surface portion extending backwardly from said end and inwardly at an obtuse angle to the inner periphery of the end portion of the article, the body also having a ground circumferential surface of frusto-conical form, the small end of the ground surface meeting said zone with the angle between the ground surface and the surface of the zone greater than a right angle.

2. In a glass article having an extended ground circumferential surface of frusto-conical form tapering in diameter toward one end of the article and terminating close to but short of said end, means for inhibiting chipping of said end of the article which comprises a smooth unground

circumferential surface of appreciable extent extending from the small end of the frusto-conical ground surface to the adjacent end of the article, the included angle between the ground and smooth unground surfaces being greater than a right angle.

3. In a glass article including a tubular portion having an extended ground circumferential surface of frusto-conical form tapering in diameter toward one end of said tubular portion and terminating close to but short of said end, means for inhibiting chipping of said end of the tubular portion which comprises a smooth unground circumferential surface of appreciable extent extending from the small end of the frusto-conical ground surface to and around said end of the tubular portion to the bore thereof, the included angle between the ground and smooth unground surfaces being greater than a right angle.

WALTER O. LUERTZING.
